Clarence L. White, Windsor, Vt., assignor to Wing-foot Corporation, Wilmington, Del., a corporation of Delaware

Application July 5, 1940, Serial No. 93,435

Term of patent 7 years

To all whom it may concern:

Be it known that I, Clarence L. White, a citizen of the United States, residing at 17 Union Street, Windsor, in the county of Windsor and State of Vermont, have invented a new, original, and ornamental Design for a Shoe Sole, of which the following is a specification, reference being had to the accompanying drawing, forming part thereof.

Fig. 1 is a plan view of a shoe sole showing my new design; and

Fig. 2 is a side elevation thereof.

I claim:

The ornamental design for a shoe sole, as shown.

CLARENCE L. WHITE.
